UNITED STATES PATENT OFFICE.

WILLIAM B. HALL, OF LANCASTER, PENNSYLVANIA.

BREECH-LOADING FIRE-ARM.

SPECIFICATION forming part of Letters Patent No. 276,808, dated May 1, 1883.

Application filed June 29, 1882. (No model.)

To all whom it may concern:

Be it known that I, WILLIAM B. HALL, of Lancaster, in the county of Lancaster and State of Pennsylvania, have invented certain new and useful Improvements in Breech-Loading Fire-Arms; and I do hereby declare the following to be a full, clear, and exact description of the invention, such as will enable others skilled in the art to which it pertains to make and use it, reference being had to the accompanying drawings, which form part of this specification.

My invention relates to an improvement in breech-loading fire-arms; and it consists, first, in the combination of a mainspring having its rear end curved upward, and a hammer which is operated by a cocking-lever from the outside, and which has a suitable recess formed in its lower end for the spring to catch against, so that when the trigger is pulled the hammer will strike the firing-pin, and then rebound to a half-cock; second, a spring which is secured to the underside of the tang and which projects downward, and has its lower curved end to bear against the rear edge of the lever at the same time that it forces the locking-bolt forward in place; third, in the combination of the catch for the fore-end, which is secured to an enlargement, extension, or lump on the bottom of the barrels by means of a set-screw which has its inner end to fit into a beveled recess, whereby the catch can be moved in one direction, but not in the other, by the tightening of the screw, and thus compensate for any wear on the moving parts in locking the barrels in place; fourth, the combination of the fore-end, a rod which moves through it, a locking-slide having its rear end made pointed, and a U-shaped spring against which this rear end bears, so that the play of the spring will be so slight that there will be no possibility of its being broken, at the same time that it gives all the force that is necessary to keep the locking-slide in place; fifth, in the arrangement and combination of parts, which will be more fully described hereinafter.

Figure 1 is a longitudinal vertical section of a gun embodying my invention. Fig. 2 is a detached view of the lock alone. Fig. 3 is a 50 detached view of the endwise-moving locking-plate and spring. Fig. 4 is a plan view of the

frame. Fig. 5 is a side elevation of the rear end of the gun-barrels. Figs. 6, 7, 8 are detail views.

A represents the frame, and B the barrels, 55 which have a breakdown movement. On the under side of the rear ends of the barrels is formed the lug C, which has its front end recessed so as to catch over the hinge pin or bolt such as is generally used. In the rear 60 edge of this lug is made a notch, in which the locking-slide D catches for the purpose of locking the barrels in a horizontal position. At a slight distance in the rear of this lug C is formed a second lug, E, which also has a recess formed in its rear edge for the locking slide or bolt to catch in. The locking slide or bolt D consists of the plate which has a hole, a, made through it sufficiently large to pass over the rear lug and to play freely back and 65 forth thereon, so that when it is pushed forward in position by means of its spring its front end will catch in the recess in the rear of the front lug, while the rear end of the opening will catch in the recess which is made in 70 the rear lug, and thus lock the barrels rigidly in position upon the stock. This locking slide or bolt has an opening, b, through its rear end, up through which passes the operating-lever G, by which the slide is drawn backward, so as 75 to release the barrels when their rear ends are to be thrown up. For the purpose of operating this slide and its lever there is secured to the under side of the tang H the flat spring I, which has its lower end curved, so as to catch 80 in a recess which is made in the rear edge of this operating-lever, and thus keep it pressed constantly forward. This flat spring also bears against the end of the slide itself, so that both the slide and the lever are acted upon by the 85 spring at the same time. By means of this construction I am enabled to dispense with all screws and other fastening devices for the purpose of locking this slide and lever in position. The upper end of this lever fits in a suitable 90 recess which is made in the rear edge of the frame or body, and its lower end projects downward a suitable distance below the trigger-plate. This projecting end, against which the finger is made to catch when the barrels are 95 to be unlocked, fits in a recess which is formed on the front end of the trigger-guard J, so as

to protect it and have it as much out of the way as possible. This recess upon the front end of the trigger-guard is formed by extending the front end of the guard forward, as shown at K, and making the front end of the guard curved, so as to conform to the shape of the operating-lever.

Through the rear end of the under side of the barrels, or what is called the "flat" of the barrels, is made a suitable opening, through which the cartridge-extractor M is passed. This extractor consists of a rod which is reduced in size at its center, and over this reduced portion is passed a sleeve, N, and spring O. Just in the rear of the sleeve is made a recess in the rod itself, in which catches a set-screw, P, which passes through the rear lug. This set-screw simply forms a stop against which the sleeve catches when the extractor is forced backward, and by thus producing a tension upon the spring the extractor is drawn inward as soon as it is left free to move, in contradistinction to being forced outward, as in most cases, and thus preventing friction against the face of the standing breech. This cartridge-extractor is operated by means of the usual lever in the fore-end, so that when the rear ends of the barrels are thrown up the lever forces the cartridge-extractor outward, so as to extract the shells. Through the forward end of the fore-end is passed the sliding rod Q, which has its rear end to bear against the locking-slide R, which is placed in a recess in the fore-end. This locking-slide has two openings made through it, so as to catch over the catches S, which are secured to the under side of the barrels, while its rear end is made pointed, so as to catch between the front ends of the U-shaped or divided spring T. This form of spring is used because when the locking-slide is pushed backward its sharpened end simply separates the ends but a very slight distance, and hence there is no possibility of the spring ever becoming broken or injured, which is not the case where any other form of spring is employed.

The catches S are formed in a single piece, and are dovetailed in a suitable projection which is formed on the under side of the barrels. In the under side of this projection is formed a beveled recess, in which the inner end of the screw U, which holds the catch in place, is made to catch. This screw bears against the beveled end of the recess and prevents the catches from moving toward the outer ends of the barrels under any circumstances; but by forcing the screw inward its end catches against the inclined end of the recess and forces the catch toward the rear end of the barrels. By means of this inclined recess and the screw the catches can be moved by simply setting up the screw, and thus all wear and tear between the curved front end of the standing breech and the rear end of the fore-end can be taken up. By this simple construction the parts can be always kept closely together, and thus the

parts will be made to operate accurately at all times.

The hinge-pin, which passes through the front end of the standing-breech, and over which the hook upon the fore-end catches, is passed movably through the front end of the breech, so that it can be turned around for the purpose of presenting a new surface to the hook at any time, in case it should become worn. Through this hinge-pin is made a hole through which is passed the screw V, which screw passes through a cap-plate at one end and into a cap-plate at the other. By moving the screw these two cap-plates W can be taken out, and thus give access to the hinge-pin for the purpose of turning it around.

The mainspring X of the lock consists of a straight rod, which has its rear end turned, as shown, so as to catch in a recess which is made in the under side of the hammer Y. This hammer is operated by a cocking-lever, Z, from the outside of the lock, and which hammer has a projection upon its rear lower corner, in which the two notches are formed. The sear catches in these notches and operates in the usual manner. When the trigger is pulled the hammer strikes the firing-pin, and then, owing to the shape of the spring and the rounded lower corner which is formed upon the hammer, the hammer automatically springs back to half-cock.

Having thus described my invention, I claim—

1. The combination of an inside hammer having its lower rear corner rounded away and a recess formed in its rear edge, and its front corner bearing on the spring when the hammer is down, with the mainspring X, having its rear end curved upward, so as to bear against the edge of the hammer and catch in the recess, substantially as shown.

2. The combination of the spring I, the lever G, and the locking-plate D, provided with the hole b for the lever to pass through, the spring being made to bear against both the plate and the lever, substantially as set forth.

3. The combination of the barrels B, having the inclined recess formed in their under side, with the adjustable catch S, the set-screw which passes through the catch into the recess, and the fore-end, substantially as described.

4. The combination of the fore-end, the end-wise-moving rod Q, the locking-plate R, the U-shaped spring T, and the catches S, fastened to the barrels, substantially as described.

5. The combination of the cartridge-extractor M, recessed on its under side, sleeve N, spring O, screw P, and the lever for moving the extractor, substantially as shown.

In testimony whereof I affix my signature in presence of two witnesses.

WM. B. HALL.
